A. KITTERMAN

WEED EXTERMINATOR

Filed Dec. 8, 1926

INVENTOR

A. Kitterman.

BY
Albert E. Dulwich
ATTORNEY

UNITED STATES PATENT OFFICE.

ALEXANDER KITTERMAN, OF PORTLAND, OREGON.

WEED EXTERMINATOR.

Application filed December 8, 1926. Serial No. 153,404.

The invention generally relates to weed exterminators and primarily has for its object to provide a new and improved weed exterminator structure in which means is provided for penetrating the ground at the position of the weed and for cutting into the heart of the weed and there forcefully depositing a substantially measured quantity of exterminating liquid.

10 In its more detailed nature, the invention resides in the provision of a new and improved weed exterminator structure in which is provided a casing having an exterminator fluid accommodating reservoir 15 therein, a forcing plunger reciprocable in the casing and means for discharging the fluid through the lower end of the device directly into the ground in and around the weed, and means whereby when the plunger 20 is actuated a substantially measured quantity of such exterminator fluid will be ejected.

The invention still further resides in the provision in a weed exterminator of the character described of a hollow plunger, 25 means for retaining constant communication between the interior of the plunger and the interior of the casing, and means for filling the exterminator fluid into the casing through the plunger without removal there- 30 of.

With the above and other objects in view that will hereinafter appear, the invention still further resides in the novel details of construction, combination and arrangement 35 of parts, all of which will be first fully described in the following detailed description, then be particularly pointed out in the appended claims, reference being had to the accompanying drawing, in which:

40 Figure 1 is a side elevation of the invention.

Figure 2 is a vertical longitudinal section, parts being shown in elevation.

Figure 3 is a plan view.

45 Figure 4 is an inverted plan view.

Figure 5 is a horizontal section taken on the line 5—5 on Figure 2.

Figure 6 is a detail perspective view of the plunger guide and measuring sleeve.

50 In the drawing, 1 indicates the casing of my improved weed exterminator which is in the nature of a hollow tube threaded at its upper and lower ends as at 2 and 3, re-

spectively. On the upper end of the casing is threaded a gland cap 4, and a closure 55 cap 5 is screwed onto the lower end, the said last mentioned cap having secured thereto as at 6 crossed blades 7 and being provided with a plurality of discharge orifices 8, the purpose for which will later be described. 60

The cap 4 accommodates the mounting of the gland packing 9 and is centrally bored as at 10 to permit reciprocation of the plunger member 11, the gland washer 9 serving to prevent leakage around the 65 plunger and through the cap 4.

The plunger member 11 is in the nature of a hollow tube, thus providing a central exterminator oil passage and reservoir 12, the upper and lower ends of the said plunger 70 member being threaded to facilitate mounting of the upper and lower closure caps 13 and 14 respectively, the former serving as a convenient means through which a suitable exterminating oil, or other liquid, may be 75 filled into the device.

The lower closure cap 14 of the plunger member 11 has a valve washer 15 secured to the bottom face thereof, as at 16, and adapted normally to close the orifices 8 in the cap 80 5, hereinbefore referred to.

By positioning the plunger member 11 in the casing 1 in the manner illustrated an annular exterminator oil chamber 17 is provided in the said casing around the said 85 plunger.

For guiding the lower end of the plunger member 11 and for assisting in the feeding and measuring of a quantity of exterminator oil to be discharged, I provide a sleeve member 18 which may be sweated into the lower end of the casing 1 or secured in any approved manner therein with its lower extremity substantially flush with the lower extremity of the said casing. This sleeve 90 is provided with a plurality of notches or grooveways 19 which extend from the upper end a considerable distance down toward the lower end of the said sleeve, the purpose for which will presently appear. 100

In the lower cap 5 is provided a measuring cup or chamber 20 which may be formed integral with the cup in the manner illustrated or by inserting a sleeve thereinto, and the internal diameter of the said cup is the same as that of the sleeve 18, thereby form- 105

ing a continuation of the chamber formed by that sleeve and which is in the nature of a measuring chamber.

- The plunger member 11 is provided near its lower end with diametrically oppositely positioned holes or apertures 21 providing communication between the hollow portion 12 of the plunger and the annular oil chamber 17 surrounding the said plunger member.
- 5 A suitable hand hold providing pin 22 is secured through the walls of the plunger member 11 at its upper end and a retractile coil spring 23 is mounted to surround the plunger member 11 between the cross pin 15 22 and the upper end of the cap 5, the upper end of the said spring being connected to the cross pin and the lower end of the said spring being threaded through the eye 24 secured to the cap 5.
- 10 In operation, the filler cap or closure cap 13 is removed and the chambers or reservoirs 12 and 17 filled with a suitable weed exterminator oil or other fluid, after which the cap is again secured in position. The 15 spring 23 serves to normally hold the plunger retracted within the casing 1, with the valve washer 15 at the bottom end thereof pressed tightly against the bottom cap 5 and closing the orifices 8 against leakage.
- 20 The plunger member 11 snugly slidably fits within the sleeve 18 and measuring cup 20 but by reason of the provision of the holes 25 21 in the lower end of the said plunger member and the grooves 19 formed in the sleeve 18 communication is always provided 30 between the interior of the plunger member and the chamber surrounding the same.

When it is desired to exterminate a weed the crossed blades at the lower end of the 40 device are forced into the ground and through the weed severing portions and substantially quartering the heart thereof and by working the end of the device around a bit, the weed is partially destroyed and the 45 ground loosened and opened about the same. By holding the casing 1 in the position just described a pulling out of the plunger member 11 by use of the hand hold cross pin 22 the plunger member is moved upwardly to 50 a position above the lowermost ends of the grooves 19 and a quantity of exterminating oil, or other fluid, allowed to flow around the plunger member bottom and through the grooves or notches 19 into the measuring 55 chamber formed by the sleeve 18 and cup 20. Upon release of the pin 22 the plunger will be quickly forced downwardly and the measured quantity of oil, or other fluid, forced 60 through the orifices 8 into the ground in the small well formed by penetration of the crossed blades 7. In practice, each such charge of exterminating fluid will constitute approximately a tablespoonful.

The upper end of the sleeve 18 may be inwardly bevelled as at 25 so that when the

parts have been disassembled and it is desired to again assemble them the lower end of the plunger member 11 may readily find its way into the sleeve without obstruction.

By using the device which I have herein disclosed it is possible to entirely exterminate weeds. Regardless of how careful one is in pulling weeds portions of the roots practically always remain and the growth of the weed is merely retarded and not killed. In the use of my device, it is possible not only to cut portions of the weed but also to inject a quantity of fluid that will positively kill not only the plant but its roots and completely exterminate the same.

From the foregoing, taken in connection with the accompanying drawing, it is thought that the novel details of construction, the manner of use and the advantages of my invention will be readily apparent to those skilled in the art to which it relates.

What I claim is:

1. A device of the class described comprising a casing, a hollow plunger movable in the casing in spaced relation to provide a surrounding liquid reservoir and having an aperture to provide constant communication between the interior of the plunger and said reservoir, means whereby exterminating fluid may be filled into the reservoir through the plunger, a discharge head carried by the casing, and means whereby when said plunger is moved in one direction a quantity of exterminating fluid will be caused to pass out of said discharge head.

2. In an exterminator of the character described, a casing, means through which exterminator fluid may be ejected from the casing, a hollow plunger for forcefully ejecting the fluid and having provision for maintaining constant communication between the interior of the plunger and the interior of the casing and for normally sealing said casing against leakage, and means facilitating filling the casing with exterminator fluid through the hollow plunger and from without the casing.

3. A device of the class described comprising a casing having a closure cap at its lower end provided with discharge orifices and a measuring cup, a plunger reciprocable in the casing and projecting from its upper end, means normally holding the plunger retracted in the casing with its lower end in the measuring cup and tightly closing the orifices, means to actuate the plunger to expel a quantity of exterminator fluid through the orifices, said plunger being hollow and provided at its upper end with a closure cap and at its lower end with an aperture communicating with the interior of the casing whereby said casing may be charged with exterminator fluid through said plunger.

4. A device of the class described comprising a casing having a closure cap at its lower end provided with discharge orifices and a measuring cup, a plunger reciprocable in the casing and projecting from its upper end, means normally holding the plunger retracted in the casing with its lower end in the measuring cup and tightly closing the orifices, a grooved sleeve for guiding the lower end of the plunger and for permitting a quantity of fluid to flow into the measuring cup when said plunger is being actuated to be expelled in the completion of the plunger's action.
5. A device of the class described comprising a casing having a closure cap at its lower end provided with discharge orifices and a measuring cup, a plunger reciprocable in the casing and projecting from its upper end, means normally holding the plunger retracted in the casing with its lower end in the measuring cup and tightly closing the orifices, means for guiding the lower end of the plunger and for permitting a quantity of fluid to flow into the measuring cup when said plunger is being actuated to be expelled in the completion of the plunger's action, said plunger being hollow and provided at its upper end with a filler cap and at its lower end with an aperture communicating with the interior of the casing whereby said casing may be charged with exterminator fluid through said plunger, said last named means comprising a sleeve having an inside diameter coincident with that of the measuring cup and having its upper edge deeply grooved to constantly provide communication between the aperture of the plunger and the interior of the casing.
6. A device of the class described comprising a casing having a closure cap at its lower end provided with discharge orifices and a measuring cup, a plunger reciprocable in the casing and projecting from its upper end, means normally holding the plunger retracted in the casing with its lower end in the measuring cup and tightly closing the orifices, means to actuate the plunger to expel a quantity of exterminator fluid through the orifices, and crossed quartering blades depending from said casing closure cap and positioned in association with said discharge orifices whereby certain of said orifices will discharge in the angles provided by adjacent portions of said blades.
7. A device of the class described comprising a tubular casing closed at its lower end which is provided with discharge orifices and a plunger guiding and measuring cup and open at its upper end to permit passage of a plunger member, a plunger member of a length and diameter for engaging the lower closed end of the casing and snugly slide-fitting the measuring cup and to project from the casing through the upper open end and which is spaced within the casing to provide a surrounding reservoir, a hand hold at the upper end of the plunger, a retractile spring surrounding the plunger and above and outside the casing and connected to the plunger and the upper casing end to normally hold the lower plunger end against the orifices to close the same and to store up energy for returning the plunger to that position when pulled upwardly and released, and a grooved sleeve for permitting a quantity of fluid to flow from the surrounding reservoir into the measuring cup when said plunger is moved upwardly out of said measuring cup.
8. A device of the class described comprising a tubular casing closed at its lower end which is provided with discharge orifices and a plunger guiding and measuring cup and open at its upper end to permit passage of a plunger member, a plunger member of a length and diameter for engaging the lower closed end of the casing and snugly slide-fitting the measuring cup and projecting from the casing through the upper open end and which is spaced within the casing to provide a surrounding reservoir, a hand hold at the upper end of the plunger, a retractile spring connected to the plunger and the upper casing end to normally hold the lower plunger end against the orifices to close the same and to store up energy for returning the plunger to that position when pulled upwardly and released, means for permitting passage of a quantity of fluid from the surrounding reservoir into the measuring cup when said plunger is moved upwardly out of said measuring cup.
9. A device of the class described comprising a tubular casing closed at its lower end which is provided with discharge orifices and a plunger guiding and measuring cup and open at its upper end to permit passage of a plunger member, a plunger member of a length and diameter for engaging the lower closed end of the casing and snugly slide-fitting the measuring cup and projecting from the casing through the upper open end and which is spaced within the casing to provide a surrounding reservoir, a hand hold at the upper end of the plunger, a retractile spring connected to the plunger and the upper casing end to normally hold the lower plunger end against the orifices to close the same and to store energy for returning the plunger to that position when pulled upwardly and released, means for permitting passage of a quantity of fluid

from the surrounding reservoir when said plunger is moved upwardly out of said measuring cup, said last named means comprising a guide sleeve registering with the measuring cup and having deep notches in its upper edge providing communication between the surrounding reservoir and the measuring cup as the lower end of the plunger

er is raised above the lower ends of said notches, said plunger being hollow and provided with a filler cap at its upper end and a communicating aperture adjacent its lower end adapted normally to communicate with the interior of the casing through one of said sleeve notches. 10

ALEXANDER KITTERMAN.
